UNITED STATES PATENT OFFICE

LOUIS C. VANDERLIP, OF ELKHART, INDIANA

ENGINE OILING DEVICE

Application filed September 4, 1928. Serial No. 303,694.

My invention relates to internal combustion engines and particularly to the lubrication system therefor.

As is well known in the internal combustion engine art the maintenance of the efficiency of the engine lubrication system is of vital importance and it has gradually been developed to a high degree by the use of filters, purifiers &c. Nevertheless it has not been possible to prevent the accumulation of water, gasoline, and other deleterious substances in the engine base or oil pan, nor to prevent certain well known injurious consequences due to such accumulation of water, and other deleterious matter, which collect at the bottom of the oil pool and are readily taken up by the oil pump which circulates the lubricant to the engine bearings.

The principal object of this invention is to provide a device which enables the oil pump to take the lubricating oil from the surface of the oil pool in the engine oil pan and thereby distribute the purer oil to the engine bearings.

Another object of the invention is to provide a device for inspiring or pumping lubricant from the surface of the engine base oil pool to insure lubricant distribution in winter when accumulated water in the engine base might freeze and close the inlet orifice of the oil suction conduit.

Other objects may be mentioned and described herein.

The preferred embodiment of my invention is illustrated in the accompany drawing, wherein,

Figure 1 illustrates a sectional view in side elevation through the base of an internal combustion engine showing the application of my invention thereto;

Fig. 2 illustrates an enlarged sectional view of the oil suction pipe and the floating hood therefor;

Fig. 3 is a view of the suction element alone; and

Fig. 4 is a section taken on line 4—4 of Figure 2.

Similar numerals of reference indicate like parts throughout the several views on the drawing.

Referring to the details of the drawing the numeral 1 indicates an internal combustion engine provided with the usual base oil pan 2 which is adapted to contain the pool of lubricating oil 3 for distribution to the engine bearings 4, 4 by a pump 5 and a pump suction conduit 6, as is well known in the art.

The conduit 6 may be arranged along the bottom of the oil pan interior and may be connected at its outer end with the tubular elbow fitting 7 by screw threads 8. An upright tubular oil suction element 9 may be screwed into the elbow fitting 7 at 10, the element 9 having a suction bore 11 which may be closed at the top end thereof by the annular head 12, said bore 11 being placed in communication with the exterior of the element 9 by a plurality of lateral orifices 13 formed adjacent the head portion 12. The numeral 14 indicates a plurality of grooves formed in the exterior of the suction element 9 and extending longitudinally thereof and substantially coextensive therewith, but which may terminate below the annular head 12 of said element, each of said grooves being in communication with one of the inlet orifices 13 adjacent the top end thereof.

Preferably, the upper end of the suction element 9 projects above the surface of the oil pool 3 and is encompassed by the hollow cylindrical hood-like element 15 which is carried by the float element 16 and adapted to be moved axially of said suction element by said float, which is buoyantly sustained in the oil pool, as the surface of said oil pool is raised or lowered by any means or for any reason.

The hood 15 is preferably a cylindrical element provided with the chamber 18 into which the element 9 telescopes slidably, the chamber 18 being closed at the top end, and said hood being built rigidly into and centrally of the float 16, both of which elements may be made of suitable sheet metal.

In operation it is obvious that the oil will be drawn upwardly along the grooves 14, the upper portions of said grooves being encompassed by the hood 15, and through inlet orifices 13 into the suction element 9, by pump

suction, and thence through pipe 6 to the pump. Also, it will be evident that the grooves 14 are in permanent communication with the pool of lubricant beneath the surface thereof, and that the oil will enter said grooves adjacent the lower end of the hood 15 and the float bottom, the latter of which is disposed close to the surface of the oil pool. Inasmuch as water and gasoline, and other deleterious matter, accumulate on the bottom of the oil pan, it will be evident that the best grade of the lubricating oil is taken from the pool and pumped to the engine bearings, and that the inlet orifices 13, being disposed high above the oil pan bottom, cannot be closed by freezing of water in the bottom of said pan.

Various immaterial modifications of my invention may be made without a departure from the spirit of the invention, and therefore, I am unwilling to limit myself to the exact form, construction, arrangement and combination of parts herein illustrated and described or uses specified.

25 I claim:

1. The combination with the lubricant container of an internal combustion engine carrying a pool of lubricant, of an upright stationary tubular lubricant suction element arranged relatively to said container and provided with an inlet orifice, a combined sleeve and float element slidably encompassing said suction element and buoyantly sustained in the lubricant pool, the lower end of said sleeve being open and immersed in the oil pool to establish communication between said oil pool and the inlet orifice of said suction element, a pump, and a suction conduit operatively connecting said pump with said suction element.

2. The combination with a lubricant container of an internal combustion engine carrying a pool of lubricant, of a stationary tubular lubricant suction element arranged in the pool of lubricant with its upper end disposed substantially above the bottom of the lubricant container and provided with a suction inlet port, a chambered hood element encompassing said suction element adjacent the upper end thereof and slidable thereon, a passage permanently connecting the suction element inlet port with said lubricant pool said passage being in communication with the lubricant pool only at its lower end, and a float to buoyantly sustain said hood in said pool of lubricant and to cause same to move axially of said suction element as the level of the pool of lubricant varies.

3. The combination with a lubricant container of an internal combustion engine carrying a pool of lubricant, of a stationary tubular lubricant suction element arranged in the pool of lubricant with its upper end disposed substantially above the bottom of the lubricant container and provided with a

suction inlet port, a chambered hood element slidably encompassing said suction element adjacent the upper end thereof, one of said elements having a longitudinal passage at the point of telescopic connection between said suction element and hood element, which permanently connects the suction element inlet port with said lubricant pool, and a float to buoyantly sustain said hood in said pool of lubricant and to cause same to move axially of said suction element as the level of the pool of lubricant varies.

4. The combination with a lubricant container of an internal combustion engine carrying a pool of lubricant, of a stationary tubular lubricant suction element arranged in the pool of lubricant with its upper end disposed substantially above the bottom of the lubricant container and provided with a suction inlet port, a headed sleeve element slidably encompassing said suction element and buoyantly sustained in the lubricant pool, one of said elements having a passage at the point of telescopic connection between said suction and hood elements which permanently connects the suction element inlet port with said lubricant pool, and means for creating partial vacuum in said suction element.

5. The combination with a lubricant container of an internal combustion engine carrying a pool of lubricant, of a stationary tubular lubricant suction element arranged in the pool of lubricant with its upper end disposed substantially above the bottom of the lubricant container and provided with a suction inlet port, and a combined sleeve and float element slidably encompassing said suction element and buoyantly sustained in the lubricant pool, said suction element having a passage which permanently connects the suction element inlet port with said lubricant pool to continuously conduct the lubricant to said suction element inlet orifice when draught is created within said suction element, said passage being substantially co-extensive with the length of said suction element.

6. The combination with a lubricant container of an internal combustion engine carrying a pool of lubricant, of a stationary tubular lubricant suction element arranged in the pool of lubricant with its upper end disposed substantially above the bottom of the lubricant container and provided with a suction inlet port adjacent the top end thereof, the upper end of said suction element being provided with a head which is arranged within said sleeve, and a combined sleeve and float element slidably encompassing said suction element and buoyantly sustained in the lubricant pool, one of said elements having a passage which permanently connects the suction element inlet port with said lubricant to continuously con-

duct the lubricant to said suction element inlet port when draught is created within said suction element.

7. The combination with a lubricant container of an internal combustion engine carrying a pool of lubricant, of a stationary tubular headed lubricant suction element arranged in the pool of lubricant with its upper end disposed substantially above the bottom of the lubricant container and provided with a lateral suction inlet port, and a combined sleeve and float element slidably encompassing said suction element and buoyantly sustained in the lubricant pool, the upper end of said sleeve being provided with an imperforate head, one of said elements having a longitudinal passage which permanently connects the suction element inlet port with said lubricant pool to continuously conduct the lubricant to said suction element inlet port when draught is created within said suction element.

8. The combination with a lubricant container of an internal combustion engine carrying a pool of lubricant, of a stationary tubular lubricant suction element arranged in the pool of lubricant with its upper end disposed substantially above the bottom of the lubricant container and provided with a suction inlet port, said suction element exterior being provided with a plurality of longitudinal grooves communicating with said inlet port, and a combined sleeve and float element slidably encompassing said suction element and buoyantly sustained in the lubricant pool to enable continuous draught of the lubricant from said pool along said suction element longitudinal grooves to said suction element inlet port when draught is created within said suction element.

9. The combination with a lubricant container of an internal combustion engine carrying a pool of lubricant, of a stationary tubular lubricant suction element arranged in the pool of lubricant with its upper end disposed substantially above the bottom of the lubricant container and provided with a plurality of suction inlet ports adjacent the top end thereof, said suction element being provided with a plurality of longitudinal exteriorly arranged grooves communicating with said inlet ports, and a combined sleeve and float element slidably encompassing said suction element and buoyantly sustained in the lubricant pool to enable continuous draught of the lubricant from said pool along said suction element grooves to said suction element inlet ports when draught is created within said suction element.

10. The combination with a lubricant container of an internal combustion engine carrying a pool of lubricant, of an upright tubular lubricant suction element arranged relatively to said container and provided with an inlet opening, a combined sleeve and float

element slidably encompassing said suction element and buoyantly sustained in the lubricant pool, said sleeve and float element establishing permanent communication between said oil pool and said suction element inlet opening, a pump, and a suction conduit operatively connecting said pump with said lubricant suction element.

11. The combination with a lubricant container of an internal combustion engine carrying a pool of lubricant, of a tubular headed lubricant suction element arranged relatively to said container and provided with an inlet opening, a combined sleeve and float element slidably encompassing said suction element and buoyantly sustained in the lubricant pool, said sleeve and float element establishing permanent communication between said oil pool and said suction element inlet opening, a pump, and a suction conduit operatively connecting said pump with said lubricant suction element.

12. In combination, an internal combustion engine lubricant container carrying a pool of lubricant, an upright tubular lubricant suction element arranged relatively to said container and provided with an inlet opening and an exterior groove which is in communication with said inlet opening, a combined sleeve and float element slidably encompassing said suction element and buoyantly sustained in the lubricant pool, said sleeve and float element establishing permanent communication between said oil pool and said suction element groove and inlet opening, regardless of the variance of the level of the pool of lubricant, and a pump operatively connected with said suction element.

13. The combination with a lubricant container of an internal combustion engine carrying a pool of lubricant, of an upright, tubular, stationary lubricant suction element arranged in the pool of lubricant with its upper end disposed substantially above the bottom of the lubricant container and provided with a suction inlet port adjacent the upper end thereof, and a combined sleeve and float element slidably encompassing said suction element and buoyantly sustained in the lubricant pool, one of said elements having a passage which establishes communication between said suction element inlet port and the pool of lubricant the central portion of said composite sleeve and float element being provided with an upwardly extended imperforate portion to accommodate the upper end of said suction element as the composite float and sleeve descends about said suction element, and a pump connected with the lower end of said suction element.

LOUIS C. VANDERLIP.

CERTIFICATE OF CORRECTION.

Patent No. 1,894,477.

January 17, 1933.

LOUIS C. VANDERLIP.

It is hereby certified that error appears in the printed specification of the above numbered patent requiring correction as follows: In the drawing, strike out the numeral "17" together with the lead line to and including the aperture; and that the said Letters Patent should be read with this correction therein that the same may conform to the record of the case in the Patent Office.

Signed and sealed this 21st day of February, A. D. 1933.

(Seal)

M. J. Moore,
Acting Commissioner of Patents.
